United States Patent Office.

STANLEY E. WORRELL, OF QUINCY, ILLINOIS.

Letters Patent No. 100,831, dated March 15, 1870.

IMPROVEMENT IN APPARATUS FOR WASHING AND ELEVATING LUMBER.

The Schedule referred to in these Letters Patent and making part of the same.

To all whom it may concern:

Be it known that I, STANLEY E. WORRELL of Quincy, in the county of Adams, and State of Illinois, have invented a new and useful Improvement in Lumber-Elevator and Washer; and I do hereby declare that the following is a full, clear, and exact description thereof, which will enable others skilled in the art to make and use the same, reference being had to the accompanying drawings forming part of this specification.

This invention relates to a new and useful Improvement in machines for elevating or "drawing" and washing lumber, whereby the labor ordinarily required for that operation is greatly diminished, while the lumber is cleaned and suitably prepared for the planing-machine; and

It consists in the construction and arrangement hereinafter described.

In the accompanying drawing—

Figure 1 represents a vertical section of the machine, through the line $z z$ of fig. 2.

Figure 2 is a plan view.

Similar letters of reference indicate corresponding parts.

I arrange on a boat or scow, A, a steam-engine or other motive power, and connect therewith a series of drawing and brushing-rollers, supported upon an adjustable frame, and so arranged that the receiving end of the frame may be directed to the water for the reception of the boards, as they are floated to the rollers by an attendant, and also so arranged that the delivery end may be directed to the pile and be raised or lowered in height.

B C and B', and C' represent the adjustable frame. E and F the receiving rollers.

G G are the brush-rollers or scrapers, one on each side of the board, and H H represent the delivery rollers.

The frame B C may be of any desired length, and any number of carrying-rollers may be employed.

The frame is jointed at R, or at any other place or places to facilitate the adjustment of the part B' and C'.

K is a windlass for adjusting the frame by means

of the chain J, which passes over the pulleys L, or the frame B' C' may be suspended in any other manner suitable for the purpose.

After the board or piece of lumber has passed between the brushes G G, I discharge one or more jets or streams of water upon it, for the purpose of cleaning off any dirt or sand which might otherwise remain.

The upper rollers on the frame are connected with springs N, which arrangement allows boards or pieces of lumber of varying thickness to be received and elevated.

O O represent the washing-tubes which extend across the frame, and discharge jets of water on to the sides of the board through perforations made for the purpose. These tubes are connected in any suitable manner with a force-pump, by which means the boards are thoroughly cleansed, as before mentioned.

P represents the carrying-rollers. The receiving-rollers and the carrying and delivery-rollers are revolved by means of belts or endless chains on the pulleys S from the motive power, in any convenient manner.

By this arrangement it will be seen that boards are drawn into the machine without being lifted from the water by hand.

Having thus described my invention,

I claim as new and desire to secure by Letters Patent—

1. The frame B C, B' C', jointed at R, substantially as and for the purposes described.

2. In combination with a machine for elevating and washing lumber, the self-adjusting receiving, carrying, and delivery-rollers, arranged to operate substantially as described.

3. The brushes or scraping-rollers G G for cleaning the lumber, arranged and operating substantially as described.

4. The perforated water-tubes O O, substantially as and for the purposes described.

STANLEY E. WORRELL.
